WHEELED TOY

Application filed September 24, 1927. Serial No. 221,705.

My invention relates to improvements in wheeled toys and it more especially consists of the features pointed out in the annexed claims.

5 The purpose of my invention is to provide a universally adaptable running gear of the tri-cycle order that may be applied to an unlimited change in shape of the body which connects the driving wheels to the steering wheel; that utilizes a single body member forming a unitary structure; that provides depending bearing members for the driving axle; that attaches the bearing members to duplicate brackets; that attaches the bearing member brackets to the body and to each other by the same means; that provides a steering column which passes through a hole formed within the wall of the body; that, if desired, may form the body of two duplicate halves with a groove formed in each half to accommodate the steering rod; that provides a spring connection between the body and the steering wheel support; that connects the steering wheel support with a cross member of the steering rod by means of crossed links; and that reduces the cost of production by forming the steering links with hook ends.

With these and other ends in view, I illustrate in the accompanying drawing such instances of adaptation as will disclose the broad underlying features of my invention without limiting myself to the specific details shown thereon and described herein.

Figure 1 is a side elevation.

35 Fig. 2 is a top plan view.

Fig. 3 is a front elevation.

Fig. 4 is a detached plan view of the steering links.

Fig. 5 is an enlarged view showing the hook ends of a steering link.

Fig. 6 is an outside enlarged elevation of a bearing support.

Fig. 7 is a side elevation partly in section of Fig. 6.

45 Fig. 8 is a detached front elevation of the bearing brackets attached to the body.

Fig. 9 is a front elevation partly in section of the steering wheel elastic connection to the body.

50 In carrying out my invention, I may use

whatever alternatives of construction that the exigencies of actual practice may demand without departing from the broad spirit of my invention.

I have found that my invention is productive of great economies in the cost of manufacture because the running gear and steering features are standardized so as to be applicable to any desired shape of body. As shown in the drawing, the body in this exemplification simulates an automobile. Other forms, such as a representation of the outline of a boat, a submarine, a cruiser, an airplane fuselage, various animals, or replicas of ancient vehicles, etc., associated with appropriate stencil or other decorations, may be used as desired. That by using a single member body which within itself combines the usual separate sides and separate ends of well known body constructions without any joining whatever, I am able to produce a line of wheeled toys that is at once unique and adaptable, in different sizes if desired, to children for re-creative play at a very low cost. This serves to place these products in the hands of the most deserving who are not always situated so as to buy expensive wheeled toys.

To follow conventional nomenclature, I am designating my invention as a "wheeled toy" but it should be noted that these goods are not toys in the ordinary sense of the word, but are serviceable utilitarian devices adapted for children to secure their allotted exercise in the open and also enable them to quickly run errands of one kind or another.

The body 1 may be formed of a single plank shaped to any desired contour, or it may be made by combining two thinner boards to form a unitary body structure only of such thickness as will give the necessary sidewise rigidity. A seat 11 is secured on the body by angle brackets 12. It can be adjusted forward of the position shown by securing the angle brackets in holes 34, as desired. The driving wheels 7 and 8 are supported on a crank shaft 6, which shaft rotates in bearings 9 secured to the lower end of the curved depending channel members 5 by means of bent-up plates 10, or in any other desired manner. These curved channels terminate immediately adja-

cent each side of the body where they rest in channeled projections 4 of the side brackets 2, to which they are riveted or otherwise secured. The side brackets 2 are duplicates of each other and are placed on opposite sides of the body so that the same fastening bolts 3 serve to hold them rigidly attached to the body after the device is assembled.

This construction simplifies the matter of production and distribution for the reason that the parts lend themselves to quantity fabrication and to ease in parcel post or other shipments. This will be clearly understood when it is recognized that the different parts of the driving and steering features are readily packed flatwise so as to occupy very little space in a carton for distribution.

The driving shaft or axle 6 is supplied with 20 pedals 31 by means of which the device is easily propelled. It is steered by a steering wheel 25 secured to the upper end of a steering rod 29, which rod passes through a diagonal hole 32 of the body 1. A bearing plate 20 and collar 27 are provided for the steering rod 25 on the upper edge of the body and a bushing 26 driven into the under edge of the body forms a bearing for the steering rod at its lower end. A cross member 28 is attached to the bottom end of the steering rod 29. It 30 has suitable openings located on opposite sides of the rod 29 to receive the hook ends 30 of the steering links 24. The rear ends of the links 24 terminate in similar hooks 30 which pass through holes formed in the cross member 35 23 of the U-shaped rear wheel support 14. These openings are located on opposite sides of the steering wheel pivot pin 16. In Fig. 4 the relation of the crossed links 24 and their 40 end attachments is shown by full lines in an extreme position and by dotted lines in the opposite extreme position.

The construction of the steering links enables me to secure further economies of production and ease of assembling by forming 45 their ends in the shape of open hooks instead of the usual eyes which require bolts and nuts to keep them in place. This feature along with others that have already been referred to enables me to secure a device of great utility 50 which is sturdy and not easily broken.

The steering wheel attachment to the body is unique in that a coil spring 22 cushions 55 the body so as to secure greater comfort to the rider. This is accomplished by attaching a U-shaped extension 15 to the upper end of the support 14 for the steering wheel 13. A pivot pin 16 is riveted or otherwise secured to the cross member 23. It passes through an opening in the extension 15, through an opening 60 in the plate 20 and into a hole 19 formed in the body. The plate 20 is U-shaped so as to permit the body to be positioned between the upturned edges of the plate where the parts are held in assembled relation by bolts 65 21 or otherwise. The pin 16 above the plate

20 has a limit pin 17 which prevents the disengagement of the pin 16 from the body 1 and plate 20. A recess or clearance opening 18 is formed in the body to accommodate the ends of the pin 17 as the body moves up and down on the coiled spring 22 which surrounds the stem 16 between the plates 20 and the member 15.

In Fig. 1 the conventional ornamentation of an automobile is shown by means of lines 75 33 which are stenciled on both sides of the body, but which form no part of the novel structural features of this present device.

In contradistinction to the usual well known type of tricycles, I place the fast and loose driving wheels, respectively 7 and 8, in advance of the steering wheel 13. This in connection with the very narrow body affords an exceptional degree of leg room free from the cramped restrictions found in wheeled devices of one kind or another as heretofore produced, and by reason of there being no outside obstructions of any kind there is no attendant liability of a child being injured, even if the device should accidentally topple over sidewise, which in ordinary usage is practically impossible.

What I claim is:

1. A side bracket having an attaching flange formed thereon, a channeled projection from the flange, a bearing member secured in the channeled projection, and a bearing unit attached to the outer end of the bearing member.

2. In wheel devices, a narrow unitary body, 100 a seat thereon projecting from either side of the body, a pair of attachable and detachable bearing supports positioned at each side of the body, separate bearings secured on the supports, means in common for both supports adapted to attach the same to the body, a crank shaft having wheels at its ends positioned in the bearings, a steering wheel and fork therefor located at the rear end of the body, means comprising a single stem for pivoting the fork to the body for movement around a vertical axis, cushioning means encircling the stem between the steering wheel fork and the body, steering means positioned on the body in advance of the seat, and links for connecting the steering means to the steering wheel.

3. In wheeled devices, a unitary narrow body of any desired shape, an adjustable seat thereon projecting from either side of the body, a pair of duplicate side brackets, means in common for both brackets adapted to secure the same to each other and onto the body, depending bearing members secured to said brackets, a crank shaft rotatable in such members, a fast wheel secured to one end of the crank shaft, a loose wheel on the other end of the crank shaft, a single steering wheel positioned at the rear end of the body, cushioning means between the body and the steer- 115 120 125 130

ing wheel, a steering rod passing through the body forward of the seat, a cross member at the lower end of the steering rod, a steering wheel support comprising a U-shaped member having a transverse portion, a pivot pin secured to the steering wheel support projecting into the body, and hook ended steering links connecting the steering rod and the steering wheel support.

10 In testimony whereof I affix my signature.
ARTIE C. CARLSON.
